UNITED STATES PATENT OFFICE.

WILLIAM W. SEELEY, OF ALBANY, NEW YORK.

BALING-PRESS.

SPECIFICATION forming part of Letters Patent No. 367,932, dated August 9, 1887.

Application filed January 3, 1887. Serial No. 223,239. (No model.)

To all whom it may concern:

Be it known that I, WILLIAM W. SEELEY, of the city and county of Albany, in the State of New York, have invented new and useful 5 Improvements in Baling-Presses, of which the following is a specification.

My invention relates to improvements in baling-presses that are operated by animal-power, the same being an improvement on 10 Patent No. 332,291, granted to me December 15, 1885; and the object of my invention is to provide a novel device for automatically increasing the leverage of the pressing mechanism to correspond to the requirements of the 15 operation of pressing. I attain this object by the mechanism illustrated in the accompanying drawings, which are herein referred to and form part of this specification, and in which—

Figure 1 is a plan view of the power end of 20 my press, that being the only part that is affected by my invention; Fig. 2, a longitudinal section of same with the pressing mechanism shown in elevation, and Fig. 3 a horizontal section with the pressing mechanism at a different point of its movement, shown in plan view.

As represented in the drawings, A is the frame-work of the press, of which only the part affected by my invention is shown.

B is a stationary shaft held by the cross-bars a of the frame-work and forming a pivotal center for the working-beams C and sweep D. The double arms or working-beams C, of which there are preferably two, one directly 35 above and the other directly below the sweep D, are each provided with a longitudinal slot, c, through which the shaft B passes, and by reason of said slots the working-beams C can receive automatically an endwise-sliding movement, whereby the leverage of the working-beams will be increased as the plunger of the press is forced inwardly, the leverage of said beams being least when in the position shown in Fig. 3 and the greatest when in the position 40 shown in Fig. 1; and it will be readily seen that this variation of leverage is in correspondence to the requirements of the work—that is to say, a quicker movement of the plunger, and consequently exerting less power, is 45 produced when there is the least resistance to the plunger and a slower movement and a cor-

responding increase of power when the plunger is meeting the greatest resistance.

The sweep D is preferably made of two beams, whose butts are fastened to a cross-yoke, d, and their opposite ends secured to each other, so that they, in connection with the cross-yoke d, are arranged to form an isosceles triangle. The cross-yoke d is provided with a central opening, through which 55 the shaft B is fitted, so as to permit the sweep D to vibrate freely thereon.

The working-beams C are pivotally connected at one end to the pitman E and at the opposite end to links F. The pitman E is 60 pivoted, as at e, to a plunger, G, which is fitted to slide freely inwardly and outwardly in the pressing-chamber a. The links F have longitudinal slots f, which engage with studs d', formed on the bridge-pieces d', that are secured to the two arms of the sweep D. The studs d' are adapted to engage in the outer 65 ends of the slots f, and the latter should be extended to a sufficient distance toward the working-beams C to permit the latter to swing 70 around on the shaft B when the rebounding movement of the plunger G occurs, as herein-after described.

The friction-rollers H are arranged at opposite sides of the press, where they will lie in 75 the path of the pitman E while the plunger is making an inward stroke, so as to aid the working-beams C in making their sliding movements. When preferred, bearing-blocks 80 may be substituted for the friction-rollers H, and when such blocks are arranged in place 85 like said rollers they will produce a like effect.

It will be seen that the working-beams C and pitman E form the two parts of a toggle-joint similar to those in common use, the material point of difference in them being the shifting of the short arm of the toggle-joint in 90 respect to its fulcrum in my device.

The operation of my press is as follows: The parts being in the position shown in Fig. 95 3, wherein the end of the working-beams C, to which the pitman E is connected, is moved outward to throw the pivot e' to its furthermost point of distance from the shaft B. The material to be pressed is to be fed into the 100 pressing-chamber a through the feed-opening a', and motion is imparted to the sweep D in

the direction indicated by the arrow on Fig. 3 to force the plunger G inwardly. At the beginning of this inward movement the plunger G will be moved quite rapidly, by reason of the long end of the working-beams C bringing about that result. As the plunger G progresses in its inward movement, the pitman E will be swung sidewise into contact with the friction-roller H at the side of the press toward which said pitman is swinging, and the effect of this contact will be to force the working-beams C to slide endwise, so as to bring their pivot e' nearer the shaft B, and thereby the leverage of the opposite end of said working-beams (that is to say, the end connected to the sweep D) will be correspondingly increased. Then as the movement of the sweep is continued in the direction indicated, and the resistance of the material being compressed increases, the working-beams C will continue to move endwise until the end of the slots c nearest the pivot e' is brought against the shaft B, and the maximum of the increase of leverage will be attained, and the same will be maintained until the center lines of the working-beams C and pitman E are brought to range in line with each other, as shown in Fig. 1; but by the continued movement of the sweep D, as soon as the pitman is carried slightly past the center line just described, the resilient action of the compressed material will cause the plunger G to rebound, thereby forcing the working-beams C to the other extremity of their movement at the side of the press from which it last started, and in effecting this movement the slots f of the links F permit said links to slide on the studs d', and

the working-beams C will slide on the shaft B until the opposite end of the slots c (that is to say, the end of said slots nearest to the link F) will bear against the shaft B, as shown in Fig. 3, when the parts will be in position for a repetition of the operation above described. When preferred, one of the working-beams C and links F may be dispensed with, and the press will be operative, and my invention includes such a modification; but as the strains are better equalized in the construction hereinabove described, I prefer to retain those parts.

I claim as my invention—

1. In a baling-press, the combination, with a stationary shaft and a sweep pivoted thereon, of working-beams provided with a longitudinal slot, whereby said working-beams are adapted to both oscillate and slide endwise on said shaft, slotted links which connect one end of said working-beams to said sweep, and a pitman which connects the opposite end of said working-beams to the plunger of the press, as and for the purpose herein specified.
2. In a baling press, the combination, with a plunger-pitman, a stationary shaft and working-beams provided with a longitudinal slot, whereby said working-beams are adapted to both oscillate and slide endwise on said shaft, of friction-wheels fixed in the path of said pitman, whereby the initial sliding movement is imparted to said working-beams, as herein specified.

WILLIAM W. SEELEY.
